SEAT CONSTRUCTION

Harry A. Campbell and George H. Vinette, Detroit, Mich., assignors to Chrysler Corporation, Highland Park, Mich., a corporation of Delaware

Application April 15, 1935, Serial No. 16,280

2 Claims. (Cl. 155—179)

This invention relates to improved resilient cushion units.

More specifically the invention relates particularly to improvements in cushion units of the character disclosed in a copending application Serial No. 16,281, filed April 15, 1935 but may be embodied to advantage in spring units of conventional construction.

One of the main objects of the invention is to provide in a resilient cushion unit, improved means for yieldably tying together the adjacent coil springs or other resilient elements of adjacent rows of said resilient elements.

Another object of the invention is to provide tying means of this character which is normally contracted laterally and adapted to expand so as to accommodate movement of one row of springs or movement of some of the springs of one row relative to the springs of the adjacent row.

A further object of the invention is to provide yieldable tying means of this kind which is particularly adapted to accommodate movement of the springs of a cushion unit which occurs when such unit is provided with flexible braces of the character set forth in the foregoing co-pending application.

A still further object of the invention is to provide, in a cushion unit having flexible braces which normally tend to rotate an edge portion of the unit about an axis during normal deflection of the unit, improved means for yieldably tying adjacent rows of the resilient members of the unit together which will accommodate such rotation of the edge portion of the unit without interfering with the normal action of the latter.

An illustrative embodiment of the invention is shown in the accompanying drawing, in which:

Fig. 1 is a vertical sectional view of a vehicle seat including a seat back portion and a seat proper both of which are provided with resilient cushion units embodying the invention.

Fig. 2 is a plan view showing the resilient cushion unit of the seat back structure illustrated in Fig. 1, as it appears when viewed from the line 2—2 of Fig. 1.

Fig. 3 is a fragmentary, vertical sectional view taken on the line 3—3 of Fig. 2.

Fig. 4 is a fragmentary, vertical sectional view taken on the line 4—4 of Fig. 2.

In the form of the invention illustrated in the drawing, the improved resilient cushion unit includes a pair of substantially rectangular frame structures 10 and 11, each of which comprises an outer border member or wire having longitudinal

15, respectively. The frame structure 11, which in the illustration shown, is mounted on a rigid supporting member 18, is formed of angle bars whereas the frame structure 10 comprises wire border portions. Extending between the longitudinal sides 13 of the frame 11 are cleats 16, and similar cleats may, if desired, be provided on the frame 10.

A plurality of rows of coil springs 17 are disposed between the frame structures 10 and 11 and the ends of the springs on at least one side of the unit are held in predetermined spaced relationship by the cleats 16. In the illustration shown, the fixed ends of the springs are secured to the frame structure 11 and the ends of the springs on the opposite side of the cushion unit are yieldably connected together by longitudinally extending tying strips 19 preferably formed of fabric and having beaded longitudinal edges in which cords 20 are disposed. The opposite edge 20 portion of the tying strips 19 are fixed to corresponding coil springs of adjacent rows thereof by wire clips or eyes 21. The longitudinal edge portions of the tying strips 19 are drawn together between the points of attachment thereof to the springs 17 in the manner illustrated in Fig. 4 and they are held in adjacent relationship by metal clips 21' so as to retain the portions of the tying strips between corresponding springs of adjacent rows in laterally contracted relationship. By virtue of this structure the tying strips 19 are rendered sufficiently expansible to accommodate limited, relative, separatory movement of the coil springs of adjacent rows.

The provision of such limited, relative, separatory movement of the springs of adjacent rows thereof is particularly advantageous in resilient cushion structures of the character which are provided with flexible bracing linkages 22 of the character illustrated in Figs. 1 and 2. Each 40 brace 22 includes a pair of converging levers 23 having their adjacent ends pivotally secured together and pivotally attached to selected coil springs 17 by a clamping member 24 comprising a strip of sheet metal of U-shaped cross 45 section which is crimped on intermediate turns of the coil springs 17 as illustrated in Figs. 1 and 2. The outer ends of the levers 23 of each flexible brace are pivotally attached to the border wire 12 of the frame 10 and to the corresponding border member 13 of the frame 11. These braces serve to hold the respective border wires with which they are associated against unintended longitudinal deflection and during normal operation of the cushion unit they permit free 55

action of the coil spring 17. When the cushion unit is compressed in the vicinity of the border portions of the frames thereof, the levers 23 confine the movement of the border portions to a substantially arcuate course. During such arcuate movement of the border portion 12 of the frame 10, for example, the expandible tying strips 19, one of which it should be understood is disposed between each pair of longitudinally extending rows of springs 17, permit relative separatory movement between the ends of the springs adjacent the frame 10 sufficient to accommodate this arcuate movement of the border portion.

15 While in the illustration shown in the drawing only one side of the spring unit is provided with expandible tying strips 19 it should be understood that in embodiments of the invention in certain articles of upholstered furniture as 20 well as bed springs and mattresses, both sides of the cushion unit may be substantially identically constructed to correspond with the flexible tying structure illustrated on only one side of the cushion unit shown in the drawing.

25 Although but one specific embodiment of the invention is herein shown and described, it will be understood that various changes in the size, shape and arrangement of parts may be made

without departing from the spirit of the invention, and it is not intended to limit its scope other than by the terms of the appended claims.

We claim:

1. A resilient cushion unit including spaced frame structures, a plurality of adjacent rows of resilient members interposed between said frame structures, and flexible tying strips between adjacent rows of resilient members having opposite edge portions secured to corresponding resilient members of adjacent rows and said opposite edge portions of said tying strips being secured together intermediate their points of attachment to said resilient members. 5

10 2. A resilient cushion unit including a row of resilient members, a second row of resilient members positioned adjacent the first mentioned row of resilient members and spaced therefrom, a fabric tying strip arranged between said rows of resilient members having opposite edge portions secured to the adjacent portions of the resilient members respectively, laterally adjacent parts of said strip being folded together intermediate its points of attachment to said resilient members, and means permanently securing portions of the edges of said folded parts together. 15
